UNITED STATES PATENT OFFICE.

EDWARD A. PERK VAN LITH, OF NEW YORK, N. Y.

ROTARY ENGINE.

1,257,156.

Specification of Letters Patent. Patented Feb. 19, 1918.

Application filed July 20, 1917. Serial No. 181,878.

To all whom it may concern:

Be it known that I, EDWARD A. PERK VAN LITH, a citizen of the United States, residing at New York city, in the county of New 5 York and State of New York, have invented new and useful Improvements in Rotary Engines, of which the following is a specification.

This invention relates to rotary engines, 10 the broad object in view being to produce an engine which is convertible or in other words adapted to be propelled by steam or by internal combustion as expediency may require.

15 A further object of the invention is to provide in conjunction with a rotor and a rotor casing, a combustion chamber within the casing, and means for varying the capacity of said combustion chamber in accordance with the fluid employed as a propelling agent.

20 A further object of the invention is to provide in conjunction with the rotor, a slide- 25 able cut off or abutment which will operate silently by reason of the formation of the 30 surface of the rotor with which said cut off co-acts.

Another object of the invention is to provide a cut off which also acts as an inlet 35 valve for the explosive mixture. Another object of the invention is to provide a simple cut off which acts also as a part of the ignition system of the engine when used as an internal combustion motor.

35 With the above and other objects in view, the invention consists in the novel construction, combination and arrangement of parts, herein fully described, illustrated and claimed.

40 In the accompanying drawings:—

Figure 1 is a vertical longitudinal section through the improved engine.

Fig. 2 is a vertical diametrical section through the same.

45 Fig. 3 is a vertical longitudinal section on an enlarged scale through the upper portion of the engine.

The engine in the preferred embodiment thereof comprises a substantially cylindrical section 1 in which is mounted a rotor 2 fast on a centrally arranged shaft 3 which extends through bearing openings 4 in the

side walls or heads 5 of the rotor casing 1. The casing 1 is shown as having the bottom portion thereof expanded to provide a supporting base 6.

The rotor 2 comprises a rim 7 and a series of spokes 8 which are flat or rectangular in cross section and pitched at an angle to form fan blades for keeping the rotor cool, 60 the casing 1 being formed with oppositely located air ports 9 to permit circulation of air through the rotor and heads 5 of the rotor casing, as shown in Fig. 2. The rotor is further provided with a plurality of expansion pockets or recesses 10, two of such pockets or recesses being shown as arranged at diametrically opposite points. Each pocket is bounded at the outer side thereof by an overhanging peripheral wall 11 while 70 the inner side thereof is defined by an inclined wall 12 of the rotor which converges from the base of the recess toward the inner periphery of the rotor to form a rounded hump or projection 13 over which the slide- 75 able cut off hereinafter referred to rides. From the rounded projecting surface 13, the periphery of the rotor again diverges from the inner periphery of the rotor casing until a low point 14 is reached, after which the periphery of the rotor again converges toward the inner periphery of the rotor casing to provide a cam surface 15 which serves to push outwardly upon the slideable cut off shown at 80 16. As shown in Fig. 2, the rotor casing is 85 formed with a channel 17 in which the peripheral portion of the rotor moves and the rotor is formed along a portion of its circumference with the oppositely located flanges 18 between which the inner end por- 90 tion of the slideable cut off 16 operates.

The cut off 16 is slideable through a guide way 19 in the upper or head portion 20 of the rotor casing and is yieldingly pressed in an inward direction so as to ride against the 95 periphery of the rotor by means of one or more compression springs 21 the inner ends of which engage retaining pins 22 on the cut off and the outer extremities of which engage other retaining pins 23 on the rotor 100 casing. To accommodate the springs 21, the cut off 16 has the outer end thereof reduced to form the lateral spaces 24 in which said springs are located as shown in Fig. 2. At

- its inner end the slidable cut off 16 has a toe or shoe portion 25 and the lower surface thereof is rounded as shown at 26 to avoid any possibility of the inner end of the cut off being caught and jammed by the rotor. It also serves to increase the area of that surface of the cut off which rides in contact with the rotor thus increasing the life and durability of the engine.
- 10 The cut off 16 is formed between the ends thereof with an explosive mixture inlet port 27 which is adapted to register with an inlet port 28 in the rotor casing when the cut off reaches the outer limit of its movement or in other words when it is riding over the hump or rounded projection 13 of the rotor. At such time explosive mixture is admitted to the combustion chamber 29 of the rotor casing which has a lateral port 30 with which the port 27 or cut off registers at such time. The slidable cut off 16 projects beyond the rotor casing and has a lateral arm or extension 31 which carries a contact 32 of the ignition system, said contact 32 being so designed as to touch the power electrode 33 of a spark plug 34 when the inner end of the cut off 16 is resting in the lowest portion of the channel in the peripheral portion of the rotor as shown in Figs. 1 and 3.
- 30 The spark plug 34 is located in a laterally offset recess 35 of the combustion chamber 29, which recess is adapted to be closed by means of a movable head 36 which is shiftable upwardly and downwardly in a cylindrical extension 37 of the combustion chamber 29, the extension chamber 37 terminating at its lower end in an annular shoulder or seat 38 so that when the head 34 is in engagement with the seat 38, the spark plug chamber 35 is closed thereby enabling the engine to be operated by steam while protecting the spark plug 35. Extending upwardly from the head 34 is a threaded adjusting stem 39 which passes through a threaded opening 40 in the rotor casing. By this means the head 36 may move to a closed position as indicated by dotted lines in Fig. 3 or it may be adjusted to any point in the length of the extension chamber 37 for the purpose of increasing or diminishing the size of the combustion chamber 29. 41 is a jam nut for fixing the adjustment of the head 36, and 42 is an air vent to admit of the easy adjustment of said head 36.
- 50 43 represents the intake pipe from the steam fuel, said pipe having a stop cock 44 incorporated therein, and 45 represents the explosive mixture intake pipe which is controlled by a stop cock 46.
- 60 In order to prevent leakage of steam or explosive mixture between the meeting faces of the rotor and rotor casing, the rotor carries pivotally mounted valves or packing members 47 arranged in peripheral recesses

48 in the rotor and yieldingly held in contact with the inner periphery of the rotor casing by means of compression springs 49. The casing is formed at a suitable point with an exhaust port 50 and one or more air vents 51.

From the foregoing description taken in connection with the accompanying drawings it will be now understood that the engine is adapted to be operated either by steam or by the ignition of an explosive mixture 75 therein, the expansion fluid acting between the cut off 16 and the rotor to propel the same. It will also be seen that the cut off 16 has a three-fold function in that in addition to its primary function as a cut off, it 80 acts as an intake valve for the explosive mixture and as the movable element of an igniter by means of which a spark is created at the proper time in the combustion chamber. By means of the movable head 36, the 85 capacity of the combustion chamber may be increased or diminished to get the best results and also for regulating the speed of rotation of the engine, and when the engine is driven by steam, the upper combustion 90 extension chamber 37 may be entirely cut off from the lower portion 29 thereof by moving the head 36 into engagement with the annular seat 38, thereby protecting the spark plug. When used as a steam engine, 95 the stop cock 46 will of course be closed and the ignition circuit will be broken. When used as an internal combustion engine, the stop cock 44 will of course be closed to exclude steam from the combustion chamber 100 of the engine.

I claim:—

1. In a rotary engine, a stationary casing, a rotor therein, and a slidable cut off operating through a guide way in the rotor casing and yieldingly held in contact with the periphery of the rotor, the rotor being formed with a channel in the periphery thereof in which the inner end of the cut off operates, the rotor being further formed with a pocket in the peripheral portion thereof bounded by an overhanging wall concentric to the center of the rotor, and a base wall having a rounded projection which coöperates with the cut off, said cut off being formed with an intake port, and the casing being formed with a combustion chamber, and intake ports for said combustion chamber with which the intake port of the abutment is adapted to register by co-action of said rounded projection with the cut off.

2. In a rotary engine, a stationary casing, a rotor therein, and a slidable cut off operating through a guide way in the rotor casing and yieldingly held in contact with the periphery of the rotor, the rotor being formed with a channel in the periphery

- thereof in which the inner end of the cut off operates, the rotor being further formed with a pocket in the peripheral portion thereof bounded by an overhanging wall 5 concentric to the center of the rotor, a base wall having a rounded projection which co-operates with the cut off, said cut off being formed with an intake port, and the casing being formed with a combustion chamber, 10 and intake ports for said combustion chamber with which the intake port of the abutment is adapted to register by co-action of said rounded projection with the cut off, a spark plug arranged at one side of said 15 combustion chamber, and an ignition circuit contact carried by said slidable cut off and adapted to co-operate with said plug for delivering the current thereto.
3. In a rotary engine, a stationary casing, 20 a rotor therein, and a slidable cut off operating through a guide way in the rotor casing and yieldingly held in contact with the periphery of the rotor, the rotor being formed with a channel in the periphery thereof in 25 which the inner end of the cut off operates, the rotor being further formed with a pocket in the peripheral portion thereof bounded by an overhanging wall concentric to the center of the rotor, and a base wall 30 having a rounded projection which co-operates with the cut off, said cut off being formed with an intake port, the casing being formed with a combustion chamber, intake ports for said combustion chamber with 35 which the intake port of the abutment is adapted to register by co-action of said rounded projection with the cut off, and a movable head in said combustion chamber for increasing or diminishing the capacity 40 thereof.
4. In a rotary engine, a stationary casing, a rotor therein, and a slidable cut off operating through a guide way in the rotor casing and yieldingly held in contact with the periphery of the rotor, the rotor being formed with a channel in the periphery thereof in which the inner end of the cut off operates, the rotor being further formed with a pocket in the peripheral portion thereof bounded 45 by an overhanging wall concentric to the center of the rotor, and a base wall having a rounded projection which co-operates with the cut off, said cut off being formed with an intake port, the casing being formed with a combustion chamber, intake ports for said combustion chamber with 50 which the intake port of the abutment is adapted to register by co-action of said rounded projection with the cut off, a valve controlled explosive mixture intake pipe communicating with the combustion chamber and controlled by said cut off, and a 55 valve controlled steam inlet pipe in communication with said combustion chamber.
5. In a rotary engine, a stationary casing, a rotor therein, and a slidable cut off operating through a guide way in the rotor casing and yieldingly held in contact with the periphery of the rotor, the rotor being formed with a channel in the periphery thereof in which the inner end of the cut off operates, the rotor being further formed with a pocket in the peripheral portion thereof bounded by an overhanging wall concentric to the center of the rotor, a base wall having a 60 movable in said combustion chamber, and means for adjusting said compression head for the purpose of increasing or diminishing the capacity of said combustion chamber.
6. In a rotary engine, a stationary casing, 65 a rotor therein, and a slidable cut off operating through a guide way in the rotor casing and yieldingly held in contact with the periphery of the rotor, the rotor being formed with a channel in the periphery thereof in which the inner end of the cut off operates, 70 the rotor being further formed with a pocket in the peripheral portion thereof bounded by an overhanging wall concentric to the center of the rotor, and a base wall having a rounded projection which co-operates with 75 the cut off, said cut off being formed with an intake port, the casing being formed with a combustion chamber, intake ports for said combustion chamber with which the intake port of the abutment is adapted to register by co-action of said rounded projection with the cut off, a spark plug arranged at one side of said combustion chamber, an ignition circuit contact carried by said 80 slidable cut off and adapted to co-operate with said plug for delivering the current thereto, a movable compression head in said combustion chamber, an annular seat against which said head is adapted to be moved, and means for shifting said compression head 85 to a position against said seat for the purpose of cutting off communication between the spark plug and the combustion chamber.
6. In a rotary engine, a stationary casing, 90 a rotor therein, and a slidable cut off co-operating through a guide way in the rotor casing and yieldingly held in contact with the periphery of the rotor, the rotor being formed with a channel in the periphery thereof in which the inner end of the cut off 95 operates, the rotor being further formed with a pocket in the peripheral portion thereof bounded by an overhanging wall concentric to the center of the rotor, a base wall having a rounded projection which co-operates with the cut off, said cut off being formed with an intake port, the casing being formed with a combustion chamber, intake ports for said combustion chamber with 100 which the intake port of the abutment is adapted to register by co-action of said rounded projection with the cut off, a valve controlled explosive mixture intake pipe communicating with the combustion chamber and controlled by said cut off, and a 105 valve controlled steam inlet pipe in communication with said combustion chamber.
7. In a rotary engine, a stationary casing, 110 a rotor therein, and a slidable cut off operating through a guide way in the rotor casing and yieldingly held in contact with the periphery of the rotor, the rotor being formed with a channel in the periphery thereof in which the inner end of the cut off operates, the rotor being further formed with a pocket in the peripheral portion thereof bounded by an overhanging wall concentric to the center of the rotor, a base wall having a 115

rounded projection which coöperates with the cut off, said cut off being formed with an intake port, the casing being formed with a combustion chamber, intake ports for said combustion chamber with which the intake port of the abutment is adapted to register by co-action of said rounded projection with

the cut off, and pivotally mounted spring pressed packing members carried by the rotor and mounted in recesses in the periphery thereof.

In testimony whereof I affix my signature.

EDWARD A. PERK VAN LITH.
